UNITED STATES PATENT OFFICE.

ERNST H. LOHRMANN, OF PROVIDENCE, RHODE ISLAND, ASSIGNOR TO FESSENDEN AND COMPANY, INC., OF PROVIDENCE, RHODE ISLAND, A CORPORATION OF RHODE ISLAND.

DESIGN FOR A HANDLE FOR SPOONS, FORKS, OR SIMILAR ARTICLES.

42,486.

Specification for Design.

Patented May 7, 1912.

Application filed December 28, 1911. Serial No. 668,337. Term of patent 14 years.

To all whom it may concern:

Be it known that I, ERNST H. LOHRMANN, a citizen of the United States, residing in the city and county of Providence, State of Rhode Island, have invented a new, original, and ornamental Design for a Handle for Spoons, Forks, or Similar Articles, of which the following is a specification, reference being had to the accompanying drawing, forming part thereof.

Figure 1 is a face view of a handle, showing my new design. Fig. 2 is a perspective view, slightly enlarged, showing a portion of the end of the handle sectioned on line 2—2 of Fig. 1.

I claim:—

The ornamental design for a handle for spoons, forks, or similar articles as shown.

ERNST H. LOHRMANN.
